UNITED STATES PATENT OFFICE

1,934,202

METAL CUTTING MACHINE

Fritz Möller, Duisburg, Germany

Application October 14, 1931, Serial No. 568,772,
and in Germany August 11, 1930

5 Claims. (Cl. 164—49)

Metal shearing machines for cutting off lengths of rolled material under movement are, as now manufactured, provided with two knives, an upper and a lower, and these knives, mounted either 5 in a reciprocating slide or on rotating shafts, are positively moved towards each other in order to effect the cutting operation. Machines so constructed have the disadvantage that when they are in the cutting position the knives must 10 also be in one particular position. The knives, moreover, must move through a certain distance without making a cut—in the case of rotating knives this distance may represent one rotation of the knife shaft—consequently the bars to be 15 cut may differ in length, according to the periphery of the circles described by the knives.

The known types of shearing mechanisms, more particularly "flying" shears, whose upper and lower knives are caused to reciprocate by a crank 20 slide guide have the further disadvantage that during the actual cutting the bar to be cut and the knives must move at identical speeds.

According to the invention, the lower knife is dispensed with, while the other knife is mounted 25 on a plunger, which is depressed by a spring or falls under gravity, an anvil, shaped like a roller and rotating during the operation of the shearing mechanism, being provided as a base or support for the material.

30 The apparatus according to the invention is so constructed that the gearing which serves to rotate the anvil also returns the plunger with the knife, after the cutting operation, to the initial position. During this time the knife is held 35 in the direction of movement of the work, while being capable of swinging outwardly, and it is so provided that it is retained in the operative position under gravity.

The accompanying drawing illustrates, by way 40 of example, one construction of the apparatus according to the invention.

Figure 1 illustrates the apparatus in side elevation,

Figure 2 is a section on the line A—B of Figure 45 1, and

Figures 3 and 4 are illustrations of detail parts.

Figure 5 is a detail view illustrating the mounting of the knife.

The apparatus according to the invention consists 50 principally of a plunger 1, which is capable of vertical reciprocation in the frame 2 under the action of a spring 3, which is confined in the head 4 of the frame 2 and presses against the upper end or shoulder of the plunger 1. The plunger 1 is provided with an easily changed

knife 5, which is so pivoted at 6 in the plunger 1 that it is held under gravity in the position shown in Figure 1 against a stop and can turn therefrom towards the right, in the anti-clockwise direction. Working in conjunction with the 60 knife is the cylindrical anvil 7, which is mounted on a shaft 8; this shaft is driven by a motor not shown in the drawing. A channel section guide 9 is provided in front of the anvil, and in it the rolled material is pushed forward in the direction 65 indicated by the arrow. The plunger 1 is held by a pawl 10 in its initial position, the pawl engaging in the notch 11 on the plunger. The pawl 10 is secured to the spindle 13 on which is also fitted the hand lever 12; the spindle 13 carries 70 a toothed segment 14 which engages in a segment 15 provided on the spindle 16. This spindle has mounted upon it a rocking member 17, the upper edge 18 of which acts upon a pawl 20 to render it inoperative. The pawl 20 is pivoted to a lever 75 21 so as to be easily movable, and this lever 21 is moved to and fro through an angle of 90° under the action of the lever 22 fixed to its spindle and a rod 23. The reciprocatory movement of the 80 pawl 20 is effected from the driving gear of the anvil 7, a gear wheel upon the shaft 8 engaging in a gear wheel 32 on a shaft 34 on which is a crank 33 connected to the rod 23.

The purpose of the pawl 20 is to engage in one of the four equally spaced indentations 24 in the 85 disc 25, after the knife has descended, in order to turn this disc through an angle of 90°. The indented disc is secured to a toothed wheel 26, which in turn engages a pinion 27. A cam 29 is keyed to the spindle 28 of the pinion 27, and 90 co-operates with a roller 30 on the plunger 1.

The apparatus operates as follows:—

If it is desired to cut through a rolled bar which has been placed under the knife 5, the lever 12 is raised against the action of its spring 31, which action releases the pawl 10. The spring 3 causes the plunger 1 to descend rapidly until it reaches the anvil 7. The knife 5 thus cuts through the bar, and it is then moved round by the rotating anvil in the direction of movement of the anvil, so that it does not impede the further movement of the bar on its way through. The knife 5 swings freely about its pivot 6 after making the cut.

At the same time as the pawl 10 is released 105 the rocking member 17 turns a certain distance to the left, so that the reciprocating pawl 20 drops into one of the indentations in the disc 25 and, on its return movement moves the disc round one quarter of a turn forward. This par- 110

tial rotation of the disc 25 causes the cam 29 to make one complete rotation, and the cam engages under the roller 30 on the plunger and returns it to the position shown in Figure 1. The 5 pawl 10 will slip back into the recess 11 under the action of the spring 31. As shown in Figure 1, the cam 29 has already raised the plunger 1 and left the roller 30. The distance of the roller 30 from the hub of the cam 29 is determined according to the stroke of the plunger 1.

10 I claim:

1. Apparatus for cutting off lengths from bars under movement, comprising a rotatable anvil, a plunger adapted to fall from an elevated position in the direction of the anvil and a knife pivoted upon the said plunger with freedom of movement to permit it to swing in the direction of travel of the bars, the said knife cutting the bar passing over the anvil and being turned about 15 its pivotal point by the bar as the bar is driven forward.

2. Apparatus for cutting off lengths from bars under movement, comprising a rotatable anvil over which the bars to be cut are fed, a plunger 25 adapted to fall from an elevated position in the direction of the anvil, a knife pivoted upon the plunger with freedom of movement to permit it to swing in the direction of travel of the bars, means for positively rotating the anvil to drive 30 forward the bar being cut and means whereby the plunger is returned to the initial position.

3. Apparatus for cutting off lengths from bars under movement, according to claim 2, comprising a rotatable cam for lifting the plunger, said cam being brought into operation after the plunger has fallen and being then rotated from 80 the means for rotating the anvil.

4. Apparatus for cutting off lengths from bars under movement, comprising a rotatable anvil, a plunger adapted to fall from an elevated position in the direction of the anvil, a knife pivotally 85 carried by the said plunger, means for rotating the anvil, a rotatable cam for lifting the plunger, an indented disc, reciprocating pawl gear for intermittently rotating said indented disc, and gearing between said indented disc and said cam 90 whereby said cam is rotated for each movement of said disc.

5. Apparatus for cutting off lengths from bars under movement, according to claim 4, comprising a pawl catch for engaging said plunger in the uplifted position, a pawl release element adapted to render the reciprocating pawl gear ineffective when said pawl catch is engaged with said plunger, inter-connecting mechanism between said pawl catch and said pawl release element, and means for releasing said pawl catch and rendering inoperative said pawl release member. 95
